United States Patent Office.

JOSEPH B. SPENCER, OF NORWICH, CONNECTICUT.

Letters Patent No. 98,116, dated December 21, 1869; antedated December 17, 1869.

IMPROVEMENT IN FLOOR-CLAMP.

The Schedule referred to in these Letters Patent and making part of the same.

To all whom it may concern:

Be it known that I, JOSEPH B. SPENCER, of Norwich, in the State of Connecticut, have invented a new and useful Improvement in Floor-Clamps; and I do hereby declare that the following is a full, clear, and exact description of the same, reference being had to the accompanying drawings, and letters of reference marked thereon, making a part of this specification, in which—

Figure 1 is a plan view; and

Figure 2 is a side elevation.

To enable those skilled in the art to make and use my invention, I now proceed to describe its construction and operation.

Similar letters in the drawings refer to like parts.

This invention is intended for tightening flooring before nailing it, and consists in a lever pivoted to a foot-piece, made so as to sit upon a floor-joist, said lever being so connected with a gripping-apparatus and a frame, that by depressing the lever, the gripping-apparatus is made to take fast hold upon the floor-joist, and the frame is made to press against the edge of the loose floor-boards, and tightly compress the same.

My foot-piece consists of an oblong plate, *a*, of about the width of ordinary floor-joists, and made to lie flat upon one of them, with a wing, *a'*, upon each side, connected with the plate by a curved neck, so as to bring the wings lower than the plate, and opposite the sides of the joist.

From the rear end of the plate *a*, two lugs, *a'' a''*, project upward, and between them is pivoted the bipartite lower end of a lever, *A*.

Near the lugs *a''*, and to opposite sides of the lever *A*, are pivoted the upper ends of arms *b b*, the lower ends of which are pivoted to clips *b' b'*, which clips are

themselves jointed upon the flat cams *c c*, having teeth upon their curved edges, said cams being jointed upon the forward ends of the wings *a'*.

By depressing the levers *A*, the cams, through the agency of the arms *b*, are rotated so as to approach one another, and bury their teeth in the floor-joist, on each side of which they are placed.

To the lever *A* are also pivoted the upper ends of bars *d d*, which bars form, with the lower cross-piece *d* and upper cross-piece *d'*, a rigid frame.

Around the upper cross-piece is placed a spiral spring, one end of which is fastened to said cross-piece, and the other end to the side of the lever *A*, so that when the lever is depressed, the spring is extended, and tends to bring it up again.

The depression of the lever causes the lower cross-piece *d* to press against the loose flooring with which it comes in contact. Such pressure, being resisted by the gripping of the cams *c* upon the floor-joist, effected, as before explained, by the same movement of the lever that operates the pressing-frame, the flooring can do nothing else than yield, and the boards are thus tightly compressed. On raising the lever again, the pressing-frame is taken from the boards at the same time that the hold of the cams upon the joist is released.

What I claim as new, and desire to secure by Letters Patent, is—

The combination of the lever *A* with the pressure-frame *d d*, gripping-cams *c c*, and connecting-rods *b b*, arranged and operating substantially as described.

JOSEPH B. SPENCER.
